UNITED STATES PATENT OFFICE.

HARNEY C. CODER, OF OKMULGEE, OKLAHOMA.

RETARDING DEVICE FOR FIRE-ESCAPES.

1,169,239.

Specification of Letters Patent. Patented Jan. 25, 1916.

Application filed May 11, 1915. Serial No. 27,431.

To all whom it may concern:

Be it known that I, HARNEY C. CODER, citizen of the United States, residing at Okmulgee, in the county of Okmulgee and 5 State of Oklahoma, have invented certain new and useful Improvements in Retarding Devices for Fire-Escapes, of which the following is a specification.

This invention relates to improvements in 10 fire escapes of the class wherein a winding drum and a suspension cable is employed, and has for one of its objects to simplify and improve the construction and increase the efficiency and utility of a device of this 15 character.

Another object of the invention is to provide a simply constructed device including a winding drum for a suspension cable and an effectual governing apparatus for con- 20 trolling the speed of descent.

Another object of the invention is to provide a simply constructed device which is compact in form, can be carried in a valise or traveling bag, and is readily attachable 25 within a room adjacent to a window and enables a person to escape through the window or other opening and to be conveyed to the ground, no matter what the elevation of the window may be.

With these and other objects in view the 30 invention consists in certain novel features of construction as hereinafter shown and described and then specifically pointed out in the claims; and in the drawings illustrative 35 of the preferred embodiment of the invention: Figure 1 is a side elevation of the improved apparatus. Fig. 2 is a front view of the same. Fig. 3 is a plan view. Fig. 4 is a detached perspective view of the gov- 40 ernor wheel of the improved device. Fig. 5 is a side elevation of the toothed wheel and its ratchet with the shaft in section. Fig. 6 is a detail illustrating a modification in suspension means.

Corresponding and like parts are referred to in the following description and indicated in all the views of the accompanying drawings by the same reference characters.

The improved device comprises a supporting plate or body 10 having brackets 11-12 extending therefrom and firmly bolted to the frame or support as shown at 13-14. A main supporting shaft 15 is carried by the brackets 11-12 at one point 55 and another shaft 16 carried by the brackets

at another point. Connected to rotate with the shaft 15 is a cable winding drum 17 to which a cable 18 is connected at one end and with a supporting snap 19 or like device at 60 the free end of the cable. The cable 18 will be of sufficient length, when unwound, to lead from the window or floor upon which the device is employed, to the ground, and will vary in length according to the height 65 of the floor or window opening from the ground. For instance, when employed upon the second floor of a building a comparatively short cable would be required, whereas, if employed upon the fifth floor of a 70 building, the cable would necessarily be much longer, as will be obvious. The size of the drum and the length of the cable will therefore be proportioned according to the 75 distance from the floor or window to the ground.

At its upper end the frame or body 10 is provided with a suspension hook 20 connected thereto by a suitable system of links, indicated at 21. The bill or point of the hook is preferably sharpened or wedge shaped to enable it to be driven into a wall, floor or behind the casing of a window, and to facilitate this action an extension 22 is formed upon the hook to receive the blows 85 of a hammer or other implement.

Mounted for rotation upon the shaft 15 is a wheel 23 having inclined teeth or recesses 24 extending entirely around the same. Connected to rotate with the shaft 15 is a ratchet wheel 22, and pivoted at 23 to the wheel 23 is a pawl 24 preferably spring pressed, and engaging the teeth of the ratchet as shown in Fig. 5. The shaft 15 is provided with a square end 25 to receive a winding crank 90 46, the object to be hereafter explained.

Mounted to swing intermediate its ends upon the shaft 16 is an arm 26 having projections 27 at its ends, the projections being preferably V-shaped and adapted to 100 alternately engage the teeth 24, as hereafter explained.

Mounted for oscillation upon the shaft 15 is a governor member 28, preferably in disk form, and relatively heavy, to produce the 105 requisite momentum when oscillated. Projecting from the member 28 is a rib 29 having slots 30-31 at opposite sides of the shaft. Extending through the slot 30 is a bolt 32 and secured adjustably in the slot 110 30 by a clamp nut 33. Extending through the slot 31 is another bolt 34 secured in place

in the slot by a clamp nut 35. By this means the bolts 32—34 may be adjusted toward or away from the shaft 15 to any desired extent within the range of the slots 30—31. Pivoted at 36 to the bolt 32 is a rod 37, while a similar rod 38 is pivoted at 39 to the bolt 34. At its outer end the rod 37 is pivoted at 40 to the arm 25 at one side of the shaft 16, while the rod 38 is pivoted at 41 to the arm 25 at the opposite side of the shaft 16.

The improved device may be constructed of any suitable size and of any suitable strength but will generally be as small as possible consistent with the strains to which 15 it will be subjected when in use, and may be employed at any place where it is necessary to escape from a fire.

The improved device may be attached permanently within the room adjacent to a window or adapted to be applied only when required, or in case of emergency. When installed permanently in a building, the hook 20 may be replaced by a ring, represented at 25 47 in Fig. 6 and adapted to be attached to a hook or other support, but when arranged for transportation or to be employed by an individual, the hooks 20—22 will be an important part of the device, as by their use 30 the apparatus may be instantly connected to any projecting portion or fixture in the room, as for instance, by being driven beneath the window casing below the window opening or driven behind the casing at the upper 35 side of the window opening.

It will be understood that the cable is fully wound upon the drum prior to the use of the device, and when the device is to be used, the user attaches the terminal member 40 19, for instance, the spring snap 19, to a band around the body, or an endless loop, in which the person to use the device places his foot, but as these numerous devices are not a part of the invention, it is not deemed 45 necessary to illustrate them as their construction is well known. When the weight of the person is applied to the cable 18, the drum 17, together with the members which are attached to the shaft 15, are rotated. The tooth to 50 which, for the time being, the portion 27 of the arm 25 is attached, is forced outwardly, which movement forces the terminal 26 at the opposite end of the arm into engagement with one of the teeth, and as the strain continues, the second member 26 is forced outwardly, which movement forces the other member 27 inwardly again and so on step by 55 step until the drum is unwound. As before stated, the member 25 is connected to the 60 relatively heavy governor disk 28 by the rods 37—38, and as the member 25 is rapidly vibrated by the alternating action of the teeth 24, the relatively heavy disk 28 is likewise vibrated and by its momentum checks 65 the movement of the arm 25 and governs

and controls the speed of the descent. If a more rapid descent is required, the bolts 32—34 are adjusted in the slots 30—31 farther from the shaft 15, and if a less rapid descent is required, the bolts are adjusted 70 toward the inner ends of the slots, as will be obvious. By this simple arrangement, the speed of descent may be readily controlled.

If two or more persons are to use the device, the second user applies the crank 46 to the shaft 15 and rotates the latter to rewind the cable upon the drum, the wheel 23, and the governor members 25 and 28, and their attachments remaining idle during the rewinding action. The device may thus be repeatedly used by simply rewinding the cable upon the drum after each action.

The improved device is simple in construction, can be strongly and cheaply constructed and of any desired material.

Having thus described the invention, what is claimed as new is:

1. In an apparatus of the class described, 90 a toothed wheel adapted to be coupled to a winding drum, an arm pivoted intermediate its ends, a pawl device pivoted intermediate its ends and alternately engaging the teeth by its terminals, and connecting means between said pawl device at each side of its pivot and to said arm at each side of its pivot.

2. In an apparatus of the class described, 100 a wheel, a pawl pivoted intermediate its ends and adapted to be alternately engaged at each side of its center of movement with said wheel, a governor device mounted to oscillate, an arm partaking of the movement of said governor device, and connecting means pivoted to said pawl at each side of its center of movement and pivoted to said arm at each side of its center of movement.

3. In an apparatus of the class described, 110 a toothed wheel adapted to be coupled to a winding drum, a governor device mounted to oscillate independently of said wheel, an arm movable with said governor device, a pawl device pivoted intermediate its ends and adapted to alternately engage the teeth 115 by its terminals, and coacting connecting means between said pawl device at each side of its center of movement and to said arm at each side of its center of movement.

4. In an apparatus of the class described, 120 a wheel, a pawl pivoted intermediate its ends and adapted to be alternately engaged at each side of its center of movement with said wheel, an arm pivoted intermediate its ends, and coupling means pivoted to said pawl device at each side of its center of movement and pivoted to said arm at each side of its center of movement.

5. In an apparatus of the class described, 130 a wheel, a pawl pivoted intermediate its ends

- and adapted to be alternately engaged at each side of its center of movement with said wheel, a governor device mounted to oscillate, an arm partaking of the movement of 5 the governor device, and connecting means pivoted to said pawl device at each side of its center of movement and pivoted to said arm at each side of its center of movement.
6. In an apparatus of the class described, 10 a toothed wheel, an arm pivoted intermediate its ends, a pawl device pivoted intermediate its ends and adapted to engage said teeth alternately at its ends, connecting means coupled to said pawl, and means for 15 adjustably coupling said connecting means to said arm.
7. In an apparatus of the class described, 20 a supporting frame, a wheel mounted for rotation upon said frame, a pawl device pivoted intermediate its ends and adapted to be alternately engaged at each side of its pivot with said wheel, an arm pivoted intermediate its ends, and connecting means between 25 said pawl device at each side of its pivot and said arm at each side of its pivot.
8. In an apparatus of the class described, 30 a wheel, a pawl pivoted intermediate its ends and adapted to be alternately engaged at each side of its pivot with said wheel, an arm pivoted intermediate its ends, and connecting means between said pawl device at each side of its pivot and said arm at each side of its pivot.
9. In an apparatus of the class described, 35 a wheel, a pawl pivoted intermediate its ends and adapted to be alternately engaged at each side of its pivot with said wheel, a governor device mounted to oscillate, an arm
- movable with said governor device, and connecting means between said pawl device at 40 each side of its pivot and said arm at each side of its center of motion.
10. In an apparatus of the class described, 45 a wheel, a pawl device mounted to swing intermediate its ends and adapted to be engaged alternately with said wheel, a governor device mounted to oscillate, and connecting means between said pawl device at each side of its center of movement with said governor device at each side of its center of 50 movement.
11. In an apparatus of the class described, 55 a wheel, a pawl device mounted to swing intermediate its ends and adapted to be engaged alternately with said wheel, a governor device mounted to oscillate, connecting means coupled to said pawl device at each side of its center of movement, and means for adjustably coupling said connecting means to said governor device at each 60 side of its center of movement.
12. In an apparatus of the class described, 65 a wheel, a pawl pivoted intermediate its ends and adapted to be alternately engaged at each side of its pivot with said wheel, a longitudinally slotted arm pivoted intermediate its ends, coupling devices movable in the slots of said arm, and connecting means between said pawl device at each side of its pivot and said coupling devices. 70

In testimony whereof I affix my signature in presence of two witnesses.
